US011828128B2

(12) **United States Patent**
Al-Mousa et al.

(10) **Patent No.:** US 11,828,128 B2
(45) **Date of Patent:** Nov. 28, 2023

(54) **CONVERTIBLE BELL NIPPLE FOR
WELLBORE OPERATIONS**

(71) Applicant: **Saudi Arabian Oil Company**, Dhahran (SA)

(72) Inventors: **Ahmed Al-Mousa**, Dhahran (SA);
Bader M. Alahmad, Dhahran (SA)

(73) Assignee: **Saudi Arabian Oil Company**, Dhahran (SA)

(*) Notice: Subject to any disclaimer, the term of this patent is extended or adjusted under 35 U.S.C. 154(b) by 51 days.

(21) Appl. No.: **17/140,298**

(22) Filed: **Jan. 4, 2021**

(65) **Prior Publication Data**

(57) **ABSTRACT**

A bell nipple includes a downhole end configured to sealingly couple to an uphole-end of a blow-out preventer. An uphole end of the bell nipple includes a first set of threads along an inner surface of the bell nipple. A thread saver is configured to be received by the uphole end. The thread saver is configured to protect the first set of threads from impact. An extension sub is configured to be received by the uphole end. The extension sub includes a downhole end with a second set of threads configured to engage with the first set of threads. An uphole end of the extension sub includes a third set of threads configured to receive a well tool.

CONVERTIBLE BELL NIPPLE FOR WELLBORE OPERATIONS

TECHNICAL FIELD

This disclosure relates to well tools mounted uphole of a blow-out preventer.

BACKGROUND

During drilling operations, a drill string extends through a bell nipple and blow-out preventer (BOP). The bell nipple receives cuttings and drilling fluids from the wellbore during drilling operations. After receiving the fluids and cuttings, the bell nipple directs the fluid and cuttings to shaker screens, where the cuttings and fluids are separated so that the drilling fluid can be reused.

As a separate operation, a well tool, such as a wireline/slickline tool, is installed atop the blow-out preventer by a shooting nipple. The well tool is exposed to well pressure during operations. Shooting nipples and bell nipples are not interchangeable as the bell nipple relies upon a static column of fluid to contain well pressure, while a shooting nipple seals the wellbore from the surrounding environment. In addition, a bell nipple relies upon the BOP to seal the wellbore in case of well pressure kick. On the other hand, the shooting nipple is installed during wireline or slickline operation and relies on wireline/slickline's BOP above it to seal against the wire or the slick in case of well control since the BOP below it can't seal against the wire or the slick.

SUMMARY

This disclosure describes technologies relating to a convertible bell nipple.

An example implementation of the subject matter described within this disclosure is a kit with the following features. A bell nipple includes a downhole end configured to sealingly couple to an uphole-end of a blow-out preventer. An uphole end of the bell nipple includes a first set of threads along an inner surface of the bell nipple. A fluid conduit defines a downward slope fluidically connected to an interior of the bell nipple. An inlet of the fluid conduit is uphole of the downhole end and downhole of the first set of threads. A valve set is positioned in-line with the fluid conduit. The valve set is configured to regulate fluid flow through the conduit. A thread saver is configured to be received by the uphole end. The thread saver is configured to protect the first set of threads from impact. An extension sub is configured to be received by the uphole end. The extension sub includes a downhole end with a second set of threads configured to engage with the first set of threads. An uphole end of the extension sub includes a third set of threads configured to receive a well tool.

Aspects of the example kit, which can be combined with the example kit alone or with other aspects, include the following. The first set of threads are ACME threads.

Aspects of the example kit, which can be combined with the example kit alone or with other aspects, include the following. The third set of threads are LTC threads.

Aspects of the example kit, which can be combined with the example kit alone or with other aspects, include the following. The valve set comprises two valves in series.

Aspects of the example kit, which can be combined with the example kit alone or with other aspects, include the following. The two valves are gate valves.

2

Aspects of the example kit, which can be combined with the example kit alone or with other aspects, include the following. One of the two valves is a hydraulically actuated valve, and the other of the two valves is a manually actuated valve.

Aspects of the example kit, which can be combined with the example kit alone or with other aspects, include the following. The thread saver includes a softer material than the bell nipple.

10 Aspects of the example kit, which can be combined with the example kit alone or with other aspects, include the following. The thread saver covers an entirety of the first set of threads when installed.

15 Aspects of the example kit, which can be combined with the example kit alone or with other aspects, include the following. The bell nipple, the valve set, and the extension sub are rated for well pressure.

An example implementation of the subject matter described within this disclosure is a method with the following features. A bell nipple is received by a blow-out preventer. The bell nipple includes ACME threads along an interior surface of an uphole end of the bell nipple. A thread saver is received by the bell nipple.

20 Aspects of the example method, which can be combined with the example method alone or with other aspects, include the following. An entirety of the ACME threads is covered by the thread saver.

25 Aspects of the example method, which can be combined with the example method alone or with other aspects, include the following. The thread saver is parted with the bell nipple. An extension sub is received by the bell nipple. The extension sub threadingly engages with the ACME threads. A well tool is received by the extension sub.

30 Aspects of the example method, which can be combined with the example method alone or with other aspects, include the following. The thread saver is parted with the bell nipple. An extension sub is received by the bell nipple. The extension sub threadingly engages with the ACME threads. A well tool is received by the extension sub.

35 Aspects of the example method, which can be combined with the example method alone or with other aspects, include the following. A valve set of the bell nipple is closed.

40 Aspects of the example method, which can be combined with the example method alone or with other aspects, include the following. The well tool and the extension sub are parted with the bell nipple. The thread saver is received by the bell nipple.

45 Aspects of the example method, which can be combined with the example method alone or with other aspects, include the following. The well tool is a wireline tool or a lubricator.

50 Aspects of the example method, which can be combined with the example method alone or with other aspects, include the following. Well pressure is retained by the bell nipple, the extension sub, and the well tool.

55 Aspects of the example method, which can be combined with the example method alone or with other aspects, include the following. Fluid is flowed through the bell nipple in an uphole direction. Fluid is flowed from the bell nipple through a conduit sloping downhill from a vertical side of the bell nipple.

An example implementation of the subject matter described within this disclosure is a wellstack with the following features. A bell nipple includes a downhole end configured to sealingly couple to an uphole-end of a blow-out preventer. An uphole end of the bell nipple includes ACME threads along an inner surface of the bell nipple. A fluid conduit defines a downward slope fluidically connected to an interior of the bell nipple. An inlet of the fluid conduit is uphole of the downhole end and downhole of the ACME threads. A valve set is positioned in-line with the fluid conduit. The valve set is configured to regulate fluid flow through the conduit.

Aspects of the example wellstack, which can be combined with the example wellstack alone or with other aspects, include the following. A thread saver is configured to be received by the uphole end. The thread saver is configured to protect the ACME threads from impact. The thread saver includes a softer material than the bell nipple.

Aspects of the example wellstack, which can be combined with the example wellstack alone or with other aspects, include the following. An extension sub is configured to be received by the uphole end. The extension sub includes a downhole end with a second set of ACME threads configured to engage with the ACME threads of the bell nipple and an uphole end with a set of LTC threads configured to receive a well tool.

Aspects of the example wellstack, which can be combined with the example wellstack alone or with other aspects, include the following. A lubricator or wireline tool sealingly engaged to the uphole end of the extension sub by the LTC threads.

Particular implementations of the subject matter described in this disclosure can be implemented so as to realize one or more of the following advantages. The time needed to switch between wireline/slickline and drilling operations is significantly reduced by the subject matter described within this disclosure.

The details of one or more implementations of the subject matter described in this disclosure are set forth in the accompanying drawings and the description. Other features, aspects, and advantages of the subject matter will become apparent from the description, the drawings, and the claims.

BRIEF DESCRIPTION OF THE DRAWINGS

FIG. 1 is a side view of a convertible bell nipple.

FIG. 2 is an illustrated list of components that can be used with aspects of this disclosure.

FIG. 3 is an illustration of the convertible bell nipple acting as a bell nipple.

FIG. 4 is an illustration of the convertible bell nipple acting as a well tool adapter, for example, for running a wireline or slickline tool.

FIG. 5 is a flowchart of a method that can be used with aspects of this disclosure.

Like reference numbers and designations in the various drawings indicate like elements.

DETAILED DESCRIPTION

During drilling operations, a bell nipple is often changed out for a shooting nipple for slickline or wireline operations. The process of changing the bell nipple for a shooting nipple and reattaching the bell nipple after the slickline or wireline operations, takes a significant amount of time and often hampers the overall drilling rate of penetration. This increase in drilling time increases total rig time and delays the onset of hydrocarbon production.

This disclosure relates to a reconfigurable bell nipple assembly that includes threaded connections, a thread saver, and adapters for other tools, such as a wireline lubricator. The assembly is reconfigurable, saving time during the drilling process, as the bell nipple does not need to be removed and reassembled to use other tools, such as a wireline lubricator. Additionally, the bell nipple includes valves on the outlet to pressure isolate, throttle fluid flow, or both, from the bell nipple.

FIG. 1 is a side view of a convertible bell nipple 100 resting atop a blow-out preventer (BOP) 102. The bell nipple

100 includes an open pipe 104 with a bolted, flanged connection 106 at a downhole end of the bell nipple 100. Typically, the flanged connection is bolted to the upper end of the BOP 102 with a gasket appropriate for the service compressed between the BOP 102 and the bell nipple 100. While described as using a bolted, gasketed connection, other connections can be used without departing from this disclosure.

The uphole end of the bell nipple 100 is typically open to 10 atmosphere (when configured to act as a standard bell nipple). The bell nipple 100 also includes ACME threads 108 at an uphole end of the bell nipple. In some implementations, the ACME threads 108 are along an inner surface of the bell nipple 100. That is, the uphole end of the bell nipple 100 acts as a female portion of a threaded connection. The square profile of ACME threads makes them very robust and resistant to damage. In addition, the square profile reduces the likelihood of cross threading. While primarily illustrated and described as using ACME threads, the uphole end of the bell nipple 100 can use any type of similarly robust threading. Alternatively or in addition, other quick-connect interfaces can be used without departing from this disclosure, such as a hammer lock connection.

Between the uphole end and the downhole end of the bell 25 nipple 100, a flow conduit 112 is fluidically connected to the open pipe 104. Typically, this conduit 112 has a downhill slope and receives drilling fluid and drill cuttings from the bell nipple 100. The conduit 112 includes one or more valves to regulate, isolate, throttle, or otherwise control a flowrate 30 through the conduit 112. In some implementations, the one or more valves can include a valve set 110. The valve set 110 can include two valves in series. In some implementations, the two valves are gate valves. Such valves are often used for isolation purposes; however, it should be noted that other isolation valves, such as ball valves, can be used without departing from this disclosure. Alternatively or in addition, valves more typically used for throttling applications, such as globe valves, can be used without departing from this disclosure. In some implementations, the valve set 110 can include more than one type of valves. For example, a throttling valve and an isolation valve can be included in series. Valves within the valve set 110 can be manually actuated, hydraulically actuated, or both. For example, one of the valves can be manually actuated, by hand, at the valve 35 location, while another valve of the valve set 110 can be hydraulically actuated, for example, remotely from a control room, or locally at a hydraulic control panel.

FIG. 2 is an illustrated list of components that can be used with aspects of this disclosure. As the bell nipple 100 is 40 reconfigurable, the bell nipple 100 can be combined with various components that can be swapped out depending upon the desired configuration. For example, the pipe 104 can include the valve set 110 and conduit 112. The conduit 112 and valve set 110 can be attached to the pipe 104 and 45 each other in a variety of ways, for example, welded, threaded, or bolted connections can be used. Connections can be connected on-site or in a manufacturing facility. In general, the fluid conduit 112 defines a downward slope. An inlet of the fluid conduit 112 is uphole of the downhole end of the bell nipple 100 and is downhole of the ACME threads. In some implementations, the valve set 110 can include a first valve 110a and a second valve 110b. In some implementations, the first valve 110a is a hydraulic gate valve, and the second valve 110b is a manual gate valve.

50 When the convertible bell nipple 100 is configured as a standard bell nipple, a thread saver 202 is configured to protect the ACME threads 108 when installed at an uphole

end of the bell nipple 100. The thread saver 202 creates an interference to prevent drill pipe or other work strings from impacting the ACME threads 108 during operations that require the bell nipple 100. In some implementations, the thread saver 202 is made of a softer material than the bell nipple 100 so that the thread saver 202 itself does not damage the ACME threads 108. Such materials can include brass or an elastomer, such as polycarbonate. In some implementations, composites such as fiber glass or carbon fiber can be used in the thread saver 202. In some implementations, the thread saver 202 covers an entirety of the ACME threads 108 when installed onto the bell nipple 100; however, other thread saver 202 geometries can be used so long as drill pipes and similar work strings are prevented from contacting the ACME threads 108 by the thread saver 202.

When configured as a shooting nipple, an extension sub 204 is threaded into the uphole end of the bell nipple 100. That is, the downhole end of the extension sub 204 includes threads 208 configured to engage with the ACME threads 108 of the bell nipple 100. Typically, the extension sub 204 acts as a male portions of a threaded connection while the bell nipple 100 acts as a female portion of the threaded connection. While primarily described and illustrated in such a configuration, the opposite configuration, with the bell nipple 100 acting as a male portion of a threaded connection and the extension sub 204 acting as a female portion of the threaded connection, can be used without departing from this disclosure. An uphole end of the extension sub 204 includes another set of threads 210 configured to receive a well tool, such as a wireline or slickline tool. While primarily described as using wireline or slickline tools, other wellbore lines, such as e-lines, coiled tubing, and umbilicals, can be used without departing from this disclosure. In some implementations, the threads 210 at the uphole end of the extension sub 204 includes an LTC thread box with LTC threads. While primarily described as using LTC threads, other threaded configurations can be used without departing from this disclosure. Similarly, other quick connect coupling mechanisms can be used, such as a hammer-lock connection.

As the bell nipple 100 can be configured in multiple ways, including pressure containment arrangements, the bell nipple 100, the valve set 110, and the extension sub 204 are rated for an expected well pressure.

FIG. 3 is an illustration of the convertible bell nipple 100 acting as a standard bell nipple. This configuration is often used during drilling operations when fluids and cuttings are circulated through the wellbore. In this configuration, the wellstack 300 includes the bell nipple 100 with its downhole end sealingly coupled to an uphole end of the BOP 102. The uphole end of the bell nipple includes the ACME threads 108 (not shown) along an inner surface of the bell nipple 100. The fluid conduit 112 defining the downward slope directs fluid from the bell nipple 100 to shaker tables 302 and other drilling fluid processing systems. The valve set 110 positioned in-line with the fluid conduit is configured to regulate fluid flow through the conduit 112, for example, to prevent the bell nipple 100 from overflowing.

The wellstack 300 includes the thread saver at the uphole end of the bell nipple. The thread saver 202 protects the ACME threads 108 (not shown as they are covered by the thread saver 202) from impact, for example, from a drill pipe or similar work string.

FIG. 4 is an illustration of the convertible bell nipple 100 acting as a well tool adapter. In this configuration, the wellstack 400 includes an extension sub 204 coupled to the

uphole end of the bell nipple 100. The extension sub 204 mates with the bell nipple 100 by the ACME threads 108 and 208. As illustrated, the extension sub 204 acts as the male portion of the threaded connection. At an uphole end of the extension sub 204, a set of LTC threads 210 receives a well tool 402, for example, a lubricator or wireline tool. The well tool 402 is sealingly engaged to the uphole end of the extension sub 204 by the LTC threads 210. That is, the threaded connection 210 is rated for well pressure. In other words, little to no fluid leaks from the LTC or ACME threads once the components are fully engaged with one another.

FIG. 5 is a flowchart of a method 500 that can be used with aspects of this disclosure. At 502, a bell nipple is received by a blow-out preventer. The bell nipple includes ACME threads along an interior surface of an uphole end of the bell nipple. That is, the bell nipple acts as the female portion of a potential threaded connection. At 504, a thread saver is received by the bell nipple. In some implementations, an entirety of the ACME threads are covered by the thread saver. Regardless of the amount of coverage, the thread saver reduces the damage to the ACME threads potentially caused by drill pipes or other work strings that pass through the bell nipple.

During drilling operations, fluid is flowed through the bell 25 nipple in an uphole direction, and fluid is then flowed from the bell nipple through a conduit sloping downhill from a vertical side of the bell nipple. Typically, the valve set 110 is closed during wireline or slickline operations. The valve set 110 can be actuated to help control the well if the need 30 arises.

In the event that wireline or slickline operations are 35 needed, at 506, the thread saver is parted with, or separated from, the bell nipple. At 508, an extension sub is received by the bell nipple. The extension sub threadingly engages with the ACME threads of the bell nipple. At 510, a well tool is received by the extension sub. The well tool can be a wireline tool, a lubricator, or a similar tool that is exposed to well pressure. Well pressure is retained by the bell nipple, the extension sub, and the well tool during the wireline or 40 slickline operations.

Once the wireline or slickline operations are completed, assuming that additional drilling operations remain, at 512, the well tool and the extension sub are parted from the bell nipple. At 514, the thread saver is received by the bell nipple. 45 After the received by the bell nipple, drilling operations can resume.

While this disclosure contains many specific implementation details, these should not be construed as limitations on the scope of what may be claimed, but rather as descriptions 50 of features specific to particular implementations. Certain features that are described in this disclosure in the context of separate implementations can also be implemented in combination, in a single implementation. Conversely, various features that are described in the context of a single implementation can also be implemented in multiple implementations separately or in any suitable subcombination. Moreover, although features may be described above as acting in certain combinations and even initially claimed as such, one or more features from a claimed combination can in some 55 cases be excised from the combination, and the claimed combination may be directed to a subcombination or variation of a subcombination.

Similarly, while operations are depicted in the drawings in a particular order, this should not be understood as requiring 60 that such operations be performed in the particular order shown or in sequential order, or that all illustrated operations be performed, to achieve desirable results. Moreover, the

separation of various system components in the implementations described above should not be understood as requiring such separation in all implementations, and it should be understood that the described components and systems can generally be integrated together in a single product or packaged into multiple products.

Thus, particular implementations of the subject matter have been described. Other implementations are within the scope of the following claims. In some cases, the actions recited in the claims can be performed in a different order and still achieve desirable results. In addition, the processes depicted in the accompanying figures do not necessarily require the particular order shown, or sequential order, to achieve desirable results.

What is claimed is:

1. A modifiable bell nipple assembly comprising:
a bell nipple comprising:
a downhole end configured to sealingly couple to an uphole-end of a blow-out preventer;
an uphole end comprising a first set of threads along an inner surface of the bell nipple;
a fluid conduit fluidically connected to an interior of the bell nipple at a downhill slope to direct fluid flowed through the bell nipple away from the bell nipple, an inlet of the fluid conduit being uphole of the downhole end and downhole of the first set of threads; and
a valve set positioned in-line with the fluid conduit, the valve set configured to regulate fluid flow through the conduit;
in a first configuration, a thread saver configured to be received by the uphole end, wherein, in the first configuration, the thread saver is configured, when installed onto the uphole end to cover the first set of threads and to protect the first set of threads from impact during operations using the bell nipple in the first configuration, wherein the valve set is configured to be opened in the first configuration; and
in a second configuration, an extension sub configured to be received by the uphole end in place of the thread saver, the extension sub comprising:
a downhole end comprising a second set of threads configured to engage with the first set of threads; and
an uphole end comprising a third set of threads configured to receive a well tool uphole of the extension sub, wherein the valve set is configured to be closed in the second configuration.
2. The assembly of claim 1, wherein the first set of threads are ACME threads.
3. The assembly of claim 1, wherein the third set of threads are LTC threads.
4. The assembly claim 1, wherein the valve set comprises two valves in series.

5. The assembly claim 4, wherein the two valves are gate valves.

6. The assembly claim 4, wherein one of the two valves is a hydraulically actuated valve, and the other of the two valves is a manually actuated valve, wherein, in the first configuration, the hydraulically actuated valve is configured to be open, and wherein, in the second configuration, the hydraulically actuated valve is configured to be closed.

10 7. The assembly claim 1, wherein the thread saver comprises a softer material than the bell nipple.

8. The assembly claim 1, wherein the thread saver covers an entirety of the first set of threads when installed.

9. The assembly claim 1, wherein the bell nipple, the valve set, and the extension sub are rated for well pressure.

15 10. A method comprising:
forming a first configuration of a bell nipple assembly by:
coupling a downhole end of a bell nipple to a blow-out preventer, the bell nipple comprising ACME threads along an interior surface of an uphole end of the bell nipple;
coupling a fluid conduit to an interior of the bell nipple at a downhill slope to direct fluid flowed through the bell nipple away from the bell nipple, an inlet of the fluid conduit being uphole of the downhole end of the bell nipple and downhole of the ACME threads;
positioning a valve set positioned in-line with the fluid conduit; and
in the first configuration:

30 covering, by a thread saver, the ACME threads of the bell nipple when the thread saver is installed onto the bell nipple, and

opening the valve set to flow fluid through the conduit; and

35 modifying a configuration of the bell nipple assembly from the first configuration to a second configuration by:

disconnecting the thread saver from the ACME threads of the bell nipple,

in place of the thread saver, connecting an extension sub to the ACME threads, and

closing the valve set to flow fluid through the conduit.

40 11. The method of claim 10, wherein connecting the thread saver to the ACME threads comprises covering an entirety of the ACME threads by the thread saver.

12. The method of claim 10, further comprising, in the second configuration:

45 connecting a well tool to the extension sub.

13. The method of claim 12, wherein the well tool is a wireline tool or a lubricator.

14. The method of claim 12, further comprising retaining well pressure by the bell nipple, the extension sub, and the well tool.
